UNITED STATES PATENT OFFICE.

JACOB HORN, OF MECHANICSBURG, OHIO.

RAILWAY-TIE.

SPECIFICATION forming part of Letters Patent No. 748,606, dated January 5, 1904.

Application filed July 27, 1903. Serial No. 167,077. (No model.)

To all whom it may concern:

Be it known that I, JACOB HORN, a citizen of the United States, residing at Mechanicsburg, in the county of Champaign and State 5 of Ohio, have invented certain new and useful Improvements in Railway-Ties, of which the following is a specification, reference being had therein to the accompanying drawings.

This invention relates to railway-ties and other similar constructions, and has for its object to provide a durable and inexpensive tie having the advantages of the ordinary wooden tie so far as elasticity and simplicity 15 in the fastening of the rails thereto are concerned.

To these ends the invention consists in certain novel features, which I will now proceed to describe and will then particularly point 20 out in the claims.

In the accompanying drawings, Figure 1 is a longitudinal sectional view of a railway-tie embodying my invention in one form. Fig. 2 is a similar view illustrating a modification; 25 and Fig. 3 is a transverse sectional view, on an enlarged scale, taken on the line $x-x$ of Fig. 1 and looking in the direction of the arrows.

In carrying out my invention I make the 30 body of the tie of a cementitious composition, preferably gravel, sand, and cement, which will harden and form practically an artificial stone. The upper or exposed surface of the tie is of wood, removably secured to the concrete body by bolting it thereto. By reason 35 of this construction the body of the tie, which is embedded in the earth, is composed of a durable, heavy, and inexpensive material which will not rot or decay, while the surface 40 or upper portion is elastic or resilient, so as to form a proper seat for the rails and permit the rails to be secured to it in the ordinary manner by spikes. Moreover, this wooden upper portion may be readily removed, if decayed or injured, and replaced by a new piece 45 of wood.

In Fig. 1 of the drawings I have shown the concrete body of the tie at 1, the same being preferably formed in a suitable box-mold. 50 Its upper face is recessed, as indicated at 2, to receive the wooden portion 3, which fits within said recess. The end portions of the

concrete body (indicated at 4) rise above the bottom of the wooden portion and preferably flush with the top thereof, so as to aid in holding the wooden portion in place, forming abutments which prevent end motion thereof. The cement body does not, however, rise as high as the top of the wooden portion at the sides thereof, said wooden portion being preferably of the same width as the cement body, as shown in Fig. 3. The rails, which are indicated at 5, therefore rest entirely upon the wood and have the benefit of the cushioning effect due to its resilience. The rails may 65 obviously be fastened directly to the wood by means of spikes 6 in the usual manner, thereby dispensing with the employment of special fastening devices or cushioning devices.

The wooden and concrete portions of the tie are connected by bolts 7, passing from the concrete body up through the wooden portion and provided on their projecting ends with nuts 8. I prefer to employ as an anchoring device for the heads of the bolts a strip or 75 strips of wood 9, embedded in the under side of the concrete body, so as to be flush with the under side thereof, and provided with recesses 10, in which the heads 11 of the bolts 7 are countersunk. Of course the anchoring-strip 80 9 need not be in a single piece, nor is it necessary that the bolt-heads should be countersunk therein. By thus bolting the wooden portion of the tie to the concrete portion said wooden portion may be readily removed and 85 renewed when necessary. The concrete body is of course more durable than the wooden portion and the renewal of the comparatively small wooden portion is much less expensive than the replacing of an entire tie of wood. 90

It will be noted that the tie proper is constructed entirely of concrete and wood without the employment of any metallic reinforcing parts, the bolts serving merely to unite the wooden portions lying on opposite sides 95 of the longitudinal axis of the tie and said wooden portions serving as reinforcing devices. Where the wooden portion 3 is continuous, as in the construction shown in Fig. 1, it serves to hold and firmly connect the rails 100 and prevent any lateral separation thereof.

The invention is of course susceptible of embodiment in various forms. For instance, I have shown in Fig. 2 a construction in

which the wooden upper portion of the tie is not continuous or in a single piece, but is made in two separate pieces, (indicated by the numeral 12,) one located under each rail, the 5 two being separated by an upward extension 13 of the concrete body.

Numerous other modifications will readily suggest themselves, and the application of the invention is not limited to railway cross-ties, but may be employed in connection with similar structures—such as switch-ties, cattle-guard timbers, bridge ties and timbers, and posts. I therefore do not wish to be understood as limiting my invention strictly to 15 the precise details of construction hereinbefore described, and shown in the accompanying drawings.

Having thus fully described my invention, what I claim as new, and desire to secure by 20 Letters Patent, is—

1. A railway-tie or similar structure comprising a body composed of cementitious composition, wooden portions embedded therein on opposite sides of the longitudinal axis 25 thereof, and bolts connecting said wooden portions and passing through the composition body at right angles to the longitudinal axis thereof, substantially as described.
2. A railway-tie comprising a body com-

posed of a cementitious composition, an upper portion of wood embedded therein and having a width equal to the width of the composition, and a length less than the length of said body, but greater than the distance between the rails, to constitute a bearing and 30 connecting member for said rails, a second wooden portion embedded in the under side of said composition body longitudinally thereof, and bolts connecting said two wooden portions and passing through the composition 35 body at right angles to the longitudinal axis thereof, substantially as described.

3. A railway-tie comprising a concrete body, a wooden bearing portion embedded in the upper portion thereof, a wooden anchoring portion embedded in the lower portion thereof, and bolts having their heads bearing in said anchoring portion and their bodies extending through the remaining portions of the tie and provided with nuts on their upper 45 ends, substantially as described.

In testimony whereof I affix my signature in presence of two witnesses.

JACOB HORN.
